UNITED STATES PATENT OFFICE.

PETER E. POST, OF KINGSTON, NEW YORK.

SKIRT-SUPPORTING BELT AND BELT-HOLDER.

SPECIFICATION forming part of Letters Patent No. 608,907, dated August 9, 1898.

Application filed September 29, 1897. Serial No. 653,532. (No model.)

To all whom it may concern:

Be it known that I, PETER E. POST, a citizen of the United States, residing at Kingston, in the county of Ulster and State of New York, have invented a new and useful Improvement in Skirt-Supporting Belts and Belt-Holders, of which the following is a specification.

My invention has for its object to provide an efficient means for securely holding in their proper positions a lady's skirt and outer belt and for preventing the slipping of either. This I accomplish by providing a belt separable from the skirt, the back part of which is made of stiff material, such as spring metal, and the front part of a flexible material, such as cloth or leather, which belt can be firmly fastened about the waist, the metal part being provided with means whereby the wearer's skirt can be secured thereto, and also, when required, carrying a removable and adjustable belt-holder, as hereinafter described.

In the drawings, Figure 1 is a perspective view of my belt and skirt-holder complete. Fig. 2 is a sectional view taken on the line 22 of Fig. 1.

In the drawings, A represents a thin band of silver, steel, copper, or other suitable metal, preferably about an inch in width and 30 six to eight inches in length and curved so as to approximately conform with the waist-line. To each end of the metal band A is secured a band or strap B of any desired flexible material, adapted to be buckled, tied, or 35 otherwise secured about the waist, so as to hold the whole firmly in place.

I provide perforations C in the band A between its edges and of such size that a hook secured to the dress-skirt may be engaged 40 therewith in order that the skirt may be suspended from this belt. The number of these holes may be varied to suit the taste of the user and the character of the skirt to be supported, a heavy skirt requiring to be sustained at more points than a lighter one to cause it to hang properly and without sagging. By making the holes round in shape and not too large they serve to prevent the skirt from slipping or twisting about without requiring the belt of the skirt to be very

tight. Above these holes C are formed notches or perforations D, preferably semicircular in shape, also adapted to receive and hold the hooks on the skirt. By this arrangement a vertical adjustment of the skirt may be effected by engaging the skirt-hooks either with the holes C or the notches D. 55

A removable belt-holder E is attached to the middle of the band A. This belt-holder is adapted to engage with the outer belt, such as is usually worn with a shirt-waist, and hold it in proper position relative to the skirt, it consisting of a plate of metal E' of suitable proportions, the upper edge of which is bent over, forming a hook F, adapted to engage 60 with the upper edge of the belt. It is provided with a spring-tongue e, having its free end bent to form a hook e', which is adapted to engage with the band and so hold the belt-holder or hook from vertical movement. 70 The band A is provided with slots G, of such size that the plate E' can pass through them and disposed near the opposite edges thereof, and which constitute a transverse slideway for the hook. The strip of metal g between 75 the slots is bent so that the plate E' can slide freely up and down between it and the edge strips g' of the band. One or more small openings g² are also provided in the strip g to receive the hook e' of the tongue of the 80 belt-holder.

When it is desired that the belt-holder should be attached, the plate E' is slipped through the slots G between the strips g and g' and the hook e' made to engage with such 85 one of the openings G or g² as may be desired to effect the proper vertical position of the belt-holder. This adjustability is a desirable feature, as it enables the wearer to use a belt of any width and to raise and lower 90 the same, so that its position relative to the skirt may be unchanged whatever the height to which the skirt may be adjusted.

The means shown whereby the outer belt-hook is secured to or connected with the belt 95 operate to prevent the hook from moving in the direction of the length of the belt and around the waist of the wearer.

What I claim as new, and desire to secure by Letters Patent, is—

The combination of a belt adapted to be secured about the waist of the wearer provided with a stiff portion A, slotted as at G, and an outer belt-holder E comprising a hook F
5 adapted to engage such outer belt, a plate adapted to slide in the said slotted part of the plate A, and a hook adapted to engage with

the part A of the belt to hold the belt-holder against accidental vertical movement, substantially as set forth.

PETER E. POST.
